COMMUNICATION SYSTEM

Hubert R. Shaw, Drexel Hill, Pa., assignor to
General Electric Company, a corporation of
New York

Application May 23, 1940, Serial No. 336,756

6 Claims. (Cl. 179—31)

My invention relates to communication systems in which three or more stations are arranged for intercommunication.

It is an object of my invention to provide certain improvements in communication systems whereby assurance of privacy of conversation between any two of the stations is obtained and at the same time a reduction in the number of line circuits employed is secured where the system involves a large number of stations.

In certain systems involving three or more intercommunicating stations having no central switching station, to secure privacy of communication between any two stations an individual line circuit is employed extending from each station to each of the other stations. An object of my invention is to avoid the use, in such systems employing no central switching station, of such individual circuits and at the same time to secure assurance of privacy.

It is a more particular object of my invention to provide, in a communication system in which a communication circuit is associated with each station and extends to every other station, means for assuring privacy of communication between any two stations by preventing connection of any third station to the communication circuit through which they are conversing.

The features of my invention which I believe to be novel are set forth with particularity in the appended claims. My invention itself, however, both as to its organization and method of operation, together with further objects and advantages thereof may best be understood by reference to the following description taken in connection with the accompanying drawing, in which the single figure represents an intercommunication system embodying my invention.

Referring to the figure I have shown an intercommunication system including three stations A, B, and C. Station A includes a sound translating apparatus 10 for transmitting and receiving sound, a relay 11, a selector switch 12, and a pair of voltage dropping resistors 13 shunted by a condenser 14. Station A also has associated with it a pair of control conductors 15, and a pair of communication conductors 16.

The apparatus 10 may comprise a transmitter and a separate receiver for interconversion of sound and electric waves, or it may conveniently comprise an electro-dynamic speaker, such speakers having the property of being able to act either as transmitter or receiver.

The relay 11 is adapted, when its coil is en-

ergized from a pair of control conductors, to connect a corresponding pair of communication conductors to the pair of leads 17 connected to the speaker in the apparatus 10.

5 The selector switch 12 has three operating buttons, 18, 19 and 20, so constructed that when one is depressed all others are released. In the normal or standby position for station A the button 18 is depressed and is locked in that position by a slide-bar 21 biased to the right by a spring 22. The shaft of button 18 extends through a slot in the slide-bar 21 and has a projection 23 which engages the body of the slide-bar when it is pulled to the right by the 10 spring 22. The buttons 19 and 20 cooperate with the slide-bar 21 in a similar way, so that if either button 19 or 20 is depressed, the slide-bar 21 is moved to the left to release the button 18 and thereafter by moving to the right locks 15 down the depressed button. The buttons 18, 19 and 20 are biased upwardly by springs 24, 25 and 26, respectively.

15 The button 18 in its depressed or standby position makes connection from a source of voltage in the apparatus 10 through the resistors 13 to the control conductors 15 and at the same time makes connection from the leads 17 to the communication conductor 16.

20 Station B comprises apparatus which is identical with that of station A, as well as with that at all other stations. Sound translating apparatus 27 at station B, which is similar to apparatus 10, includes a source of voltage, which is connected through a pair of resistors 28 to a pair of control conductors 31, when a button 29 of a selector switch 30 is in its depressed position. A pair of leads 32 from the speaker in the apparatus 27 are connected by contacts operated by the switch button 29 to a pair of communication conductors 33.

25 Sound translating apparatus 34 at station C is identical with apparatus 10 and 27 at station A and B. A source of voltage in apparatus 34 is connected through a pair of resistors 35 and contacts operated by a button 36 of a switch 37 to a pair of control conductors 38. The button 36 also connects a pair of leads 39 from the speaker in apparatus 34 to a pair of communication conductors 40. The button 18 at station 30 A and the button 41 at station B are adapted when depressed to connect stations A or B respectively to the pairs of conductors 38 and 40. The buttons 20 and 42 at stations A and C are likewise adapted to connect stations A and C respectively to the pairs of conductors 31 and 33.

The buttons 43 and 44 at stations B and C are adapted when depressed to connect stations B and C respectively to the pairs of conductors 15 and 16.

In operation, for example, if the operator at station B desires to communicate privately with station C he depresses button 41 which simultaneously releases the button 29. The button 41 connects the coil of relay 45 at station B to the control conductors 38. The button 36 is depressed, as is the corresponding button at every station during standby condition, and therefore voltage is present on the conductors 38. This voltage is sufficient to operate the relay 45, which therefore connects the communication conductors 32 of station B through the contacts of button 41 to the communication conductors 40, which are connected to the communication conductors 39 at station C. Conversation may be carried on through that connection.

No other station may interrupt this communication because the current drawn by the coil of relay 45 produces a voltage drop across resistors 35 so that the voltage on conductors 38 is just sufficient to hold relay 45 closed, and is not sufficient to operate any other relay. Therefore, even though the operator at station A depresses the button 19, the relay 11 cannot be operated and station A cannot interfere with the conversation between stations B and C. Since the button 29 is released on depression of the button 41, the operator at station A cannot communicate with station B by depressing the button 20, since the resistors 28 are disconnected from the control conductors 31 and voltage is removed therefrom.

When the conversation between stations B and C is finished, the operator at station B need only depress the button 29 to place his station in standby condition again. If he fails to depress the button 29 but leaves his station in communicating condition with station C, the operator at station C can communicate with any station other than station B merely by depressing the proper button. For example, by depressing the button 44, the button 36 is released which disconnects stations B and C. The button 44 connects the coil of relay 46 to control conductors 15, which have enough voltage to close the contacts of the relay and place station C in communication with station A.

For each station in the system it is necessary to provide one pair of communication conductors and one pair of control conductors which two pairs are connected to every other station in the system. It is thus necessary at any point to provide not more than twice as many pairs of conductors as there are stations in the system. In the usual system it is necessary in order to have private communication to provide one pair of conductors between each pair of stations in the system. In a system using my invention therefore it is necessary to have $2n$ pairs of conductors, while in usual systems it is necessary to have

$$\frac{n(n-1)}{2}$$

pairs of conductors. The maximum number of pairs of conductors necessary in such usual systems at any one point is

$$\frac{n^2}{4}$$

while with my system the maximum number of pairs is $2n$ at any point. For systems having 10

or more stations, those which embody my invention become very much more economical as the number of stations is increased. For example, with 30 stations it is necessary to provide 60 pairs of conductors for a system embodying my invention, while it is necessary to provide 225 pairs of conductors at some points in other systems.

It is obvious that as many more stations as needed may be added to such a system as I have shown if a pair of control conductors and a pair of communication conductors be supplied for each additional station. There must also be supplied at each station an additional button in the selector switch, since at each station there must be one standby button and one button for every other station on the system.

With the type of selector switches which I have shown for convenience in the drawing, it is possible to depress two or more buttons at once, so that simultaneous communication may be had between 3 or more stations. For example, if station A desires to communicate with both stations B and C, he must depress both buttons 19 and 20 simultaneously. Assuming that the buttons 29 and 36 are depressed in standby position, station A is connected to both stations B and C. It is of course necessary that the voltage supplied through the resistors 13, 28 and 35 be properly poled for interconnection.

Since the mode of operation where two or more buttons may be depressed simultaneously introduces a slight possibility that some station may interrupt an existing communication by depressing one button corresponding to a communicating station and another button corresponding to a station in standby condition, I find it of advantage in certain cases to provide selector switches in which only one button may be depressed at a time. Such switches are commonly used as station selector switches in household radio receivers. It is, of course, within the scope of my invention to use any type of selector switch for performing the functions explained above.

While I have shown a particular embodiment of my invention, it will, of course, be understood that I do not wish to be limited thereto, since different modifications may be made both in the circuit arrangement and instrumentalities employed and I aim by the appended claims to cover any such modifications as fall within the true spirit and scope of my invention.

What I claim as new and desire to secure by Letters Patent of the United States is:

1. In an intercommunication system including at least three stations, a pair of line circuits extending between said stations, means for connecting one of said stations normally to one of said line circuits, the other stations being normally disconnected from said one line circuit, means to apply voltage of greater than a predetermined value to the other of said line circuits, means in each other station responsive to voltage on said other line circuit above said predetermined value to connect said other station to said one line circuit, and means to reduce said voltage on said other line circuit after operation of said voltage responsive means to a value below said predetermined value, whereby the corresponding voltage responsive means of a third station is thereafter unresponsive to voltage on said other line circuit to connect said third station to said one line circuit.

2. In an intercommunication system including at least three stations, a pair of line circuits ex-

tending between said stations, means for connecting one of said stations normally to one of said line circuits, the other stations being normally disconnected from said one line circuit, means to supply voltage of greater than a predetermined value to the other of said line circuits, a relay in each other station arranged when energized to connect said other station to said one line circuit, means at said other station to energize said relay at the respective station from said other line circuit, said relay being operative only in response to voltage greater than said predetermined value and maintaining said other station connected to said one line circuit in the presence of voltage of a lesser value, and means effective upon operation of said relay to reduce the voltage on said other line circuit to said lesser value, whereby the corresponding relay at a third station is thereafter unresponsive to voltage on said other line circuit to connect said third station to said one line circuit.

3. In an intercommunication system including three or more stations, a pair of line circuits extending between said stations, an impedance, means for connecting one of said stations normally to one of said line circuits, the other stations being normally disconnected from said one line circuit, means to supply voltage of greater than a predetermined value through said impedance to the other of said line circuits, a relay in each other station arranged when energized to connect said station to said one line circuit, and means at said other station to energize said relay from said other line circuit, said relay being operative only in response to voltage greater than said predetermined value and maintaining said other station connected to said one line circuit in the presence of voltage of a lesser value, said impedance being effective upon operation of said relay to reduce the voltage in said other line circuit to said lesser value by the voltage drop resulting from current through said impedance, whereby the corresponding relay at a third station is thereafter unresponsive to voltage on said other line circuit to connect said third station to said one line circuit.

4. In combination, at least three intercommunicating stations, a communication circuit and a control circuit corresponding to each station and extending between said stations, means to connect each station to its communication circuit and to supply voltage to said control circuits, means in each station to connect said station to the communication circuit of any desired station, said means in each station including means responsive to voltage on the control circuit of said desired station to effect said connection, and

- means to reduce the voltage on the control circuit of said desired station after said voltage responsive means has effected said connection to a value sufficiently low that the voltage responsive means of any third station will not respond to said voltage to effect connection of said third station to the communication circuit of said desired station, whereby said third station is prevented from intercepting communication between two intercommunicating stations.
5. In combination, at least three intercommunicating stations, a communication circuit and a control circuit corresponding to each station and extending between said stations, means in each station to connect it to its communication circuit and to apply voltage to its control circuit or alternatively to connect it to the communication circuit of any desired station, said means in each station including means responsive to voltage on the control circuit of said desired station to effect said last connection, and means to reduce the voltage on the control circuit of said desired station after said voltage responsive means has effected said connection to a value sufficiently low that the voltage responsive means of any third station will not respond to said voltage to effect connection of said third station to the communication circuit of said desired station, whereby said third station is prevented from intercepting communication between two intercommunicating stations.
6. In combination, at least three intercommunicating stations, a communication circuit and a control circuit corresponding to each station and extending between said stations, means in each station to connect it to its communication circuit and to supply voltage to its control circuit or alternatively to connect it to the communication circuit of a desired station, said means including an electromagnetic relay operated by voltage on the control circuit of said desired station to effect said last connection, said relay comprising an operating coil and a switch operated thereby, said coil being adapted to close said switch only upon energization by voltage substantially higher than the voltage necessary to maintain it closed, and means to reduce the voltage on the control circuit of said desired station after said relay has effected said connection to a value lower than said higher voltage so that the relay of any third station will not respond to said voltage to effect connection of said third station to the communication circuit of said desired station, whereby said third station is prevented from intercepting communication between two intercommunicating stations.

HUBERT R. SHAW.
